[57] CLAIM

The ornamental design for a bike light, as shown.

DESCRIPTION

FIG. 1 is a front plan view of the bike light of the present invention, with the cord broken away to indicate indeterminate length;

FIG. 2 is a back plan view of the bike light of FIG. 1;
FIG. 3 is a left side plan view of the bike light of FIG. 1;
FIG. 4 is a right side plan view of the bike light of FIG. 1;
FIG. 5 is a top plan view of the bike light of FIG. 1; and,
FIG. 6 is a bottom plan view of the bike light of FIG. 1.
